UNITED STATES PATENT OFFICE.

HIRAM W. HARRIS, OF NEW YORK, N. Y.

DESIGN FOR A GAME-COUNTER.

SPECIFICATION forming part of Design No. 20,713, dated May 12, 1891.

Application filed March 13, 1891. Serial No. 384,958. Term of patent 7 years.

To all whom it may concern:

Be it known that I, HIRAM W. HARRIS, of New York, in the county and State of New York, have originated and produced a new 5 Design for Counters for Games, of which the following is a specification.

My design relates to disk-shaped counters used in connection with various games.

My design consists of a circular body or 10 central portion, a contrasting border or edge portion, and a central flower-like figure on the body or central portion.

The accompanying drawing is a face view of a device embodying my design.

15 A designates the body or central portion. B designates the contrasting border or edge portion, and C designates the flower-like figure at the center of the body portion. I have

also shown two rings or bands D' D² around the flower-like figure. The flower-like figure 20 is shown as of an open construction having a series of radial leaves or petals. The surfaces of the completed article may be flush in all parts—that is, having no projecting parts.

What I claim as my invention, and desire 25 to secure by Letters Patent, is—

The design for a game-counter, substantially as shown and described.

In testimony whereof I have signed my name to this specification in the presence of 30 two subscribing witnesses.

HIRAM W. HARRIS.
